UNITED STATES PATENT OFFICE

WILLIAM T. BAUMAN, OF CHICAGO, ILLINOIS, ASSIGNOR TO UNIVERSAL FORM CLAMP CO., OF CHICAGO, ILLINOIS, A CORPORATION OF ILLINOIS

BAR SUPPORT AND SPACER

Application filed February 17, 1930. Serial No. 429,116.

The main objects of this invention are to provide an improved bar support and spacer for use in reinforcing systems of concrete construction work; and to provide a bar support and spacer which may be fabricated out of a single piece of wire.

An illustrated embodiment of this invention is shown in the accompanying drawings, wherein:

Figure 1 is a perspective of an improved bar support and spacer.

Fig. 2 is a fragmentary top plan showing two reinforcing bars supported on two of the improved devices, part of the mold soffit being shown in dotted outline.

Fig. 3 is a transverse vertical section, taken on the line 3-3 of Fig. 2, the dotted lines showing the reinforcing bars preparatory to being pressed downwardly into their seats.

Fig. 4 is an enlarged end elevation of one of the devices, showing also part of a reinforcing bar.

The common types of bar support and spacer heretofore in use generally included a plurality of supporting members secured to spacing strips which spaced them uniformly from one another. In the manufacture of those devices, the supporting members and spacing strips were separately fabricated and then assembled in units. Each unit consisted of separately formed parts of different shapes which required several different dies. It was also necessary for the manufacturer to carry in stock a large supply of each part of the units.

In the construction herein shown, the improved bar support and spacer comprises a single piece of wire which is fabricated to form both the bar supporting part and the spacing part. This obviates the necessity of carrying in stock a large number of parts of different sizes and shapes and also obviates the necessity of welding.

The support and spacer is preferably made of wire of comparatively heavy gauge, which

possesses the necessary rigidity and which may be bent to the desired shape.

The reinforcing system involves the use of a plurality of reinforcing bars 1, disposed horizontally above a falsework, such as a joist soffit 2, and supported in substantially parallel spaced relation by a plurality of the improved supports and spacers.

Each of the improved devices comprises a wire which is bent to form two or more substantially U-shaped supporting saddles 3 for receiving the bars 1. The side arms of the saddles are crimped inwardly to define restricted throats 4 of slightly less width than the reinforcing bars, so that it is necessary to press the bars through the throats when placing them in the saddles. The side arms of the saddles are yieldable so as to permit expansion of the throats when the bars are inserted.

The inner arms of two adjacent saddles are connected by a horizontal portion 5, which serves as a spacing rod for spacing the reinforcing bars the required distance from each other. The outer side arms of the saddles are bent outwardly to provide spacers 6 which are adapted to engage the side walls of the mold, not shown.

In the construction shown, the base of each saddle is bent at its central portion to provide a pair of downwardly diverging legs 7 and a horizontal foot 8 arranged to form a substantially triangular support which is located in a plane disposed at substantially right angles to the plane of the saddles 3.

In operation, the improved devices are placed on the falsework at the desired intervals and the reinforcing bars are then pressed downwardly into their seats. The bar supports and spacers embodying these improvements are exceedingly simple in construction and operation, comparatively inexpensive to manufacture and very rigid when set up.

I claim:

A bar support and spacer comprising a

single piece of wire bent to form a pair of substantially U-shaped saddles disposed in a single plane and spaced from each other, the outer arms of said saddles being bent outwardly, the inner arms of said saddles being bent inwardly and connected together, the base parts of said saddles being bent to form depending triangular supports intersecting the plane of said saddles, said saddles having restricted throats.

Signed at Chicago this 14th day of February, 1930.

WILLIAM T. BAUMAN.
